(57) **CLAIM**

The ornamental design for a display screen or portion thereof with transitional graphical user interface, as shown and described.

DESCRIPTION

FIG. 1 is the first image in a sequence for a display screen or portion thereof with transitional graphical user interface showing my new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof; and,

FIG. 10 is the tenth image thereof.

The appearance of the transitional image sequentially transitions between the images shown in FIGS. 1-10. The process or period in which one image transitions to another forms no part of the claimed design.

The dashed broken lines showing portions of the display screen or portion thereof with graphical user interface are for environmental purposes only and form no part of the claimed design.
